UNITED STATES PATENT OFFICE

ARTHUR L. FAWCETT, OF PUMPKIN, TEXAS

PUMP

Application filed May 20, 1931. Serial No. 538,850.

My invention relates to certain new and useful improvements in pumps for water and oil wells and it particularly has for its object to provide a pump in which the weight 5 of the plunger rod and its piston are taken advantage of to raise the water or oil from the well.

Heretofore, pumps have been provided whereby on the upstroke of the plunger rod 10 and its piston the water is lifted while on the down stroke the water chamber of the pump is recharged. My invention has for an object to reverse this order and to charge the pump chamber on the upstroke of the 15 plunger and to force the water to the surface on the downward stroke of the plunger to expel the water from the well.

Further, it is an object to provide a simple, inexpensive pump, the parts of which 20 may be economically manufactured and easily assembled, and to provide a structure in which those parts subject to wear or requiring replacement from time to time may readily and conveniently be removed and replaced.

25 Other objects will in part be obvious and in part be pointed out hereinafter.

To the attainment of the aforesaid objects and ends, the invention still further resides in the novel details of construction, combination and arrangement of parts, all of 30 which will be first fully described in the following detailed description, then be particularly pointed out in the appended claims, reference being had to the accompanying drawings, in which:

Figures 1 and 1^a when joined at the dot and dash lines A—B and read together constitute a longitudinal section of the invention showing the plunger going down, the arrows indicating the direction of flow of the 40 water or oil as the case may be.

Figures 2 and 2^a when joined at the dot and dash line C—D and read together are similar views with the plunger going up.

45 Figure 3 is a cross section on the line 3—3 of Figure 1.

Figure 4 is a cross section on the line 4—4 of Figure 1.

50 Figure 5 is a cross section on the line 5—5 of Figure 1.

Figure 6 is a perspective view of the valve cage and its back check valve.

In the drawings, in which like numerals of reference indicate like parts in all of the figures, the outer barrel of the pump is shown 55 as composed of sections 1—1 and 41 coupled together by screw couplings 2 and 40, the latter being a reducing coupling.

A bushing 3 is secured within the lower 60 end of the outer barrel by suitable means 4. The bushing 3 is counterbored as at 5 and has the entrance to the counterbore bevelled as at 6 so that in fitting the inner barrel 9 it will conveniently slide into place in the counterbore 5.

65 The counterbore 5 provides a shoulder 7 or seat for the packing ring 8 that is located between the shouldered end 10 of the inner barrel 9 and the seat 7. The weight of the barrel 9 on the packing 8 serves to effect a 70 water-tight joint. The barrel 9 is fitted into the bushing 3 with a snug fit.

Held by retaining friction within the lower 75 end of the inner barrel 9 is a valve cage and valve unit composed of an upper ring 12 bored and tapered centrally as at 13 and a base ring 14 connected with the upper ring 12 by vertical posts 11. The ring 14 has an outer annular groove in which is located a suitable packing 15 that assists in effecting a water-tight joint between the base 14 of the valve cage and the inner barrel 9.

The base 14 of the valve cage is internally threaded at 16 and receives a tubular valve seat member 17, the latter having notches 85 18 for the reception of a suitable tool by means of which it may be screwed into and out of place as desired.

The free valve 19 moves up and down between the base ring 14 and the top ring 12 90 and is guided by the uprights 11. The valve 19 is of the spool type and has a disk washer 20 secured by a cap screw 21 to effect a tight seal with the tubular valve seat member 17 when resting thereon.

95 The inner barrel 9 preferably just above the valve cage is provided with ports 22 to effect communication from the inside of the barrel 9 to the space between the barrels 9 and 1 so that water being forced from the 100

barrel 9 will pass through these ports 22 into the space between the inner and outer barrels and upwardly as indicated by arrows in Figure 1.

6 The upper end of the inner barrel 9 is internally threaded as at 23 to receive a bushing 24 that is bored to serve as a bearing for the plunger rod 25, the latter having a piston 26 provided with suitable packing 10 rings 27, the piston fitting the inner barrel 9.

Secured within the upper end of the section 1 of the outer barrel is an upper bushing 28, the lower part of which is provided with lugs 29 that extend from the inner barrel 9 to the outer barrel section 1 and these lugs 29 are provided with passages or ports 30 that register with similar ports 32 in the outer barrel and ports 31 in the inner barrel. The inner barrel is also provided with an outer annular groove 42 registering with the ports 31 so that should the inner barrel turn and throw the ports 31 and 30 out of alignment, it will not effect the functions of these parts.

25 The upper bushing 28 at its upper end is provided with a valve seat ring 33 which bridges the space between the inner and outer barrels. This ring 33 is provided with liquid passes 34 and a conical valve seat 35 through which passes the water is expelled toward the top of the well when the valve 36 is forced off the seat 35. The valve 36 is in the nature of a sleeve that slides up and down on the inner barrel 9 and has guide lugs 37 on its outer face and a conical valve seat portion 38 to cooperate with the valve seat 35.

35 The plunger rod 25 is preferably made in sections screw-connected together as at 39 and 44, the screw end 39 being of a size and threaded to fit the threads of the opening 13 in the valve cage so that when it is desired to remove the valve cage after pulling the plunger rod out, the plunger rod may be reversed and screwed into the valve cage and the valve cage pulled out by using the plunger rod.

40 It will be seen that the section 1 of the outer barrel extends only a short distance above the top of the inner barrel 9 and there it is connected with the extension pipe section 41 by the reducing joint 40.

45 The bushing 28 is held in place in the outer barrel by suitable set screws 43 as shown.

50 So far as described the operation of the invention is as follows:

55 When the plunger rod 25 is reciprocated by any suitable power mechanism (not shown) on the upstroke of the rod water will be drawn into the inner barrel 9 through the bottom opening of the barrels 1 and 9 causing the valve 19 to unseat. Water will not be withdrawn from the space between the barrels back through the openings 22 because of the fact that the valve 36 remains seated to 60 close the out-passes 34. It should be under-

stood that when the pump is immersed in the water or other liquid in the well, the fluid will enter the barrel 9 above the piston 26 through the openings 32—30—31 and be expelled through such openings on the upstroke 70 of the plunger rod 25.

On the down stroke of the plunger rod the valve 19 will immediately seat and close off the escape of fluid from the pump through the bottom openings of the inner and outer barrels, thus forcing the fluid to pass through the openings 22 into the space between the barrels and upwardly through the passes 34, raising the valve 36 from the seat 35 and passing upwardly to the top of the well. At the same time the fluid will flow into the inner barrel 9 above the piston 26 through the ports 32—30—31 as before referred to. These ports 32—30—31 may be termed breather ports since they have no further function than to permit a small quantity of liquid to flow into and out of the barrel 9 above the plunger piston to prevent the formation of a vacuum in the inner barrel 9 between the piston 26 and the bushing 24.

90 From the foregoing description, taken in connection with the accompanying drawings, it is thought the complete construction, operation and advantages of my invention will be clear to those skilled in the art to which it relates.

What I claim is:

1. In a pump, an outer casing, upper and lower bushings secured to and in said casing, an inner casing spaced from said outer casing by said bushings, breather ports effecting communication between said inner casing and the exterior of said outer casing adjacent said upper bushing, said inner casing having ports adjacent said lower bushing to effect communication between the inside of said inner casing and the space between said inner and outer casings, a valve cage with a valve located in said inner casing adjacent its lower end, said upper bushing having a ring with a valve seat and liquid passes effecting communication between the space below and above the ring, a valve slideable on said inner casing and gravitating to engage said ring valve's seat to close said passes, a bushing secured in the upper end of said inner casing, and a plunger rod passing through said last named bushing and carrying a piston within said inner casing.

105 2. In a pump, an outer cylindrical barrel composed of pipe sections coupled together and extending from the top of the well into the liquid within the well, a bushing in each end of the lower pipe section, the lower bushing having a counterbore and seat, an inner barrel passing through the upper bushing and having its lower end located within said counterbore and on said seat, said inner barrel having a snug fit in said bushing, means sealing the passage of water between said 110

bushing and said inner barrel, a back check valve unit carried in the lower part of said inner barrel and a bushing secured in the upper end of said inner barrel, a plunger rod passing through said upper bushing and carrying a piston within said inner barrel, ducts from the inside of said inner barrel to the outside of said outer barrel and located adjacent said upper bushing, ports through said inner barrel adjacent said valve unit, said upper bushing having liquid passes from the space between said barrels below said upper bushing to the space between the same above the said upper bushing, and a valve slidably on said inner barrel for closing said passes.

3. In a pump, an outer cylindrical barrel composed of pipe sections coupled together and extending from the top of the well into the liquid within the well, a bushing in each end of the lower pipe section, the lower bushing having a counterbore and seat, an inner barrel passing through the upper bushing and having its lower end located within said counterbore and on said seat, said inner barrel having a snug fit in said bushing, means sealing the passage of water between said bushing and said inner barrel, a back check valve unit carried in the lower part of said inner barrel and a bushing secured in the upper end of said inner barrel, a plunger rod passing through said upper bushing and carrying a piston within said inner barrel, ducts from the inside of said inner barrel to the outside of said outer barrel and located adjacent said upper bushing, ports through said inner barrel adjacent said valve unit, said upper bushing having liquid passes from the space between said barrels below said upper bushing to the space between the same above the said upper bushing, and a valve slidable on said inner barrel for closing said passes, said upper bushing having a conical valve seat and said slidable valve having a conical valve seat portion cooperating with the valve seat of said upper bushing.

4. In a pump, an outer cylindrical barrel composed of pipe sections coupled together and extending from the top of the well into the liquid within the well, a bushing in each 50 end of the lower pipe section, the lower bushing having a counterbore and seat, an inner barrel passing through the upper bushing and having its lower end located within said counterbore and on said seat, said inner barrel having a snug fit in said bushing, means sealing the passage of water between said bushing and said inner barrel, a back check 55 valve unit carried in the lower part of said inner barrel and a bushing secured in the upper end of said inner barrel, a plunger rod passing through said upper bushing and carrying a piston within said inner barrel, ducts from the inside of said inner barrel to 60 the outside of said outer barrel and located 65

adjacent said upper bushing, ports through said inner barrel adjacent said valve unit, said upper bushing having liquid passes from the space between said barrels below said upper bushing to the space between the same above the said upper bushing, and a valve slidable on said inner barrel for closing said passes, said lower bushing having a bevelled end leading to its counterbore.

5. In a pump, an outer cylindrical barrel composed of pipe sections coupled together and extending from the top of the well into the liquid within the well, a bushing in each end of the lower pipe section, the lower bushing having a counterbore and seat, an inner barrel passing through the upper bushing and having its lower end located within said counterbore and on said seat, said inner barrel having a snug fit in said bushing, means sealing the passage of water between said bushing and said inner barrel, a back check valve unit carried in the lower part of said inner barrel and a bushing secured in the upper end of said inner barrel, a plunger rod passing through said upper bushing and carrying a piston within said inner barrel, ducts from the inside of said inner barrel to the outside of said outer barrel and located adjacent said upper bushing, ports through said inner barrel adjacent said valve unit, said upper bushing having liquid passes from the space between said barrels below said upper bushing to the space between the same above the said upper bushing, and a valve slidable on said inner barrel for closing said passes, said upper bushing having a conical valve seat and said slidable valve having a conical valve seat portion cooperating with the valve seat of said upper bushing, said lower bushing having a bevelled end leading to its counterbore. 105

6. In a pump, an outer cylindrical barrel composed of pipe sections coupled together and extending from the top of the well into the liquid within the well, a bushing in each end of the lower pipe section, the lower bushing having a counterbore and seat, an inner barrel passing through the upper bushing and having its lower end located within said counterbore and on said seat, said inner barrel having a snug fit in said bushing, means sealing the passage of water between said bushing and said inner barrel, a back check valve unit carried in the lower part of said inner barrel and a bushing secured in the upper end of said inner barrel, a plunger rod passing through said upper bushing and carrying a piston within said inner barrel, ducts from the inside of said inner barrel to the outside of said outer barrel and located adjacent said upper bushing, ports through said inner barrel adjacent said valve unit, said upper bushing having liquid passes from the space between said barrels below said upper bushing to the space between the same 110 115 120 125 130

above the said upper bushing, and a valve
slidable on said inner barrel for closing said
passes, said back check valve unit comprising
a cage having a base part fitted into said in-
5 ner barrel with retaining friction, and a
valve in said cage, said last named valve hav-
ing a packing disk, and a seat ring threaded
into the base part of said cage to cooperate
with said disk.
